UNITED STATES PATENT OFFICE.

GEORGE HENRY WALKER, OF WORCESTER, ENGLAND, ASSIGNOR TO HEENAN & FROUDE LIMITED, OF CHAPEL WALKS, MANCHESTER, ENGLAND.

HYDRAULIC BRAKE FOR DYNAMOMETERS.

Application filed November 3, 1925, Serial No. 66,670, and in Great Britain November 11, 1924.

This invention relates to hydraulic brakes or dynamometers for absorbing and measuring the power developed by rotating shafts and more particularly to improvements in the type of hydraulic brake or dynamometer in which a rotor mounted upon a shaft is enclosed in an outer casing, vanes or pockets being formed both in the rotor and the casing in which the water circulates creating eddies or vortices which destroy power when the rotor is revolved.

The specification of my prior British Patent No. 24949 of 1910 described an hydraulic brake or dynamometer of the type above referred to in which the vanes of the casing and rotor are provided with passages for water or air, the water passages being utilized to maintain a continuous supply of fresh cool water to the brake, and the air passages to maintain atmospheric pressure at the centre of the vortices formed by the rotation of water in the brake. The specification No. 24949 of 1910 and the specifications of other of our prior British patents, also describe means for controlling the outlet of water from the casing partly with the object of maintaining a suitable working temperature and partly with the object of controlling the consumption of power.

According to the present invention means are provided for supplying all or a portion of the water to the brake or dynamometer at a rate of feed which is proportionate to the speed of rotation of the shaft, and also if desired, for recirculating the water leaving the rotor through the water passages in the vanes of the rotor.

The invention will be described with reference to the accompanying drawings.

Fig. 1 is a front elevation of one form of the invention applied to a reversing type of dynamometer in which there are two sets of power absorbing elements, one arranged to rotate clock-wise and the other anti-clock-wise.

Fig. 2 is a longitudinal section of same.

Fig. 3 is an end elevation of same.

Fig. 4 is a front elevation of another form of the invention applied to a non-reversing type of dynamometer.

Fig. 5 is an end elevation of same.

As shown in Figs. 1 to 3 the invention is applied to a reversing type of dynamometer in which there are two sets of power absorbing elements—the rotors A—one ar-

ranged to rotate in a clockwise direction and the other in a counter-clockwise direction, means being provided so that the supply of water can be cut off from one or other of the compartments as desired and the whole of the power be absorbed in the other compartment. The main supply of water is admitted to the casing through an inlet valve B and a flexible pipe B¹ connected to a branch pipe b connected to the two rotor compartments A¹.

In the form of the invention shown in Figs. 1 to 3 the centrifugal effect of the revolving rotor A of whichever half of the dynamometer is absorbing power is utilized to promote a flow of water through holes or passages a formed in the vanes of the rotor so that there is a re-circulation of the water or a portion of the water from a part of the casing where the pressure is high to a part of the casing where the pressure is low and from which the rotor obtains its supply of water.

Each rotor A is hollow and is fitted with a gland a¹ surrounding the shaft A² through which it can draw a suitable supply of water from a compartment C formed in the casing. A further gland a² around the shaft A² prevents leakage of water from this compartment.

After entering the hollow rotor A the water passes through the holes a formed in the vanes of the rotor so as to communicate with a point a³ in the power-absorbing pockets a⁴ where under running conditions, the pressure is low. At the points a³ of the pockets a⁴ the pressure of the water due to centrifugal force is higher than at the points where the holes a enter into the pockets and this pressure is transferred to the space d between the rotor A and the casing D. The water is conveyed from this zone of higher water pressure through the ports or passages e to a valve E so arranged that the area for the passage of water through the ports in the valve can be varied by gradual stages from fully open to fully shut. The outlet side of this valve communicates through the passage e¹ with the compartment C in the casing which feeds the rotor suction.

The compartment C is fitted with a release valve F which may conveniently be of the spring loaded pattern arranged to open and discharge waste water to a funnel F¹ or

similar device whenever the pressure of water in the rotor suction compartment rises above a pre-determined figure. Under normal running conditions the rate at which water leaves the rotor suction compartment A¹ is generally governed by the speed at which the rotation of the rotor induces a flow of water through the holes in the rotor vanes and the rate at which water enters this

10 compartment is governed by the opening of the main inlet valve B. Thus when water enters the compartment in greater quantities than it leaves through the rotor suction, a pressure immediately builds up in the compartment and opens the release valve F, which may be replaced by an overflow weir or the like.

Between the inlet valve B and the rotor suction compartment a valve G may be inserted if desired though such valve is not essential to the working of the invention. The valve G is normally kept closed by a spring g and is fitted with a cylinder g¹ and piston g² on one side of which connection is made 20 by pipes g³ to that chamber d in which, when power is being destroyed, the water pressure is high, while the other side of the piston g² is connected to the compartment C from which the water is supplied to the rotor. Thus when the difference in pressure between the two sides of the piston g² due to the destruction of power is sufficiently great to overcome the resistance of the spring g, the valve opens, admitting fresh water to 30 the chamber C. This fresh water mixes with the water re-circulated through the rotor valve, and keeps the temperature of the brake or dynamometer within suitable limits.

Immediately upon the supply of power being removed from the shaft of the brake, however, the difference in pressure between the two sides of the piston g² disappears, and the valve G closes under the influence of the spring g, thus shutting off the supply 40 of fresh water, preventing the dynamometer being unduly filled with water which would create a severe resistance to rotation next time the dynamometer should be started up.

50 Figs. 4 and 5 show a non-reversing type of dynamometer with a single rotor. In the form of the invention illustrated in these figures water is fed to the power absorbing portions of the dynamometer by means of a separate pump driven by gearing or by direct coupling to the shaft of the dynamometer, a valve being interposed between the pump and the power absorbing cups of the dynamometer by which the amount of water entering the casing of the dynamometer can be regulated.

55 The supply of fresh water which is necessary for cooling purposes, is carried through flexible pipe B² between a fixed portion of the dynamometer to a connection on the swivelling portion. The cool water passes

from the pipe B² to the suction side of a pump H which may be of centrifugal or other type driven by chains h or other gearing, from the shaft A² of the dynamometer, and therefore rotating at a speed which is 70 proportional to that of the shaft A². The pump may if desired, be directly coupled to a free end of the dynamometer shaft, or it may be mounted upon the dynamometer shaft, as will be easily understood. 75

The water discharged by the pump A is conveyed through a hand operated valve K by which the quantity of water passing can be regulated, and from this point it branches into a compartment of the casing of the 80 dynamometer, from which holes drilled through the vanes of the non-rotating stator, carry the water into a point in the power-absorbing pockets where under working conditions the pressure is low, as previously described. Ports are formed in the casing 85 communicating with a point where under working conditions the pressure of water is high to convey the water to an outlet valve F of similar construction to the outlet valve 90 F described in connection with Figs. 1 to 3 by which the flow of water can be controlled. This valve F may conveniently discharge direct to waste through a funnel F¹ or similar device. 95

If desired a by-pass pipe can be inserted to connect the discharge from valve F with the compartment C, and allow re-circulation of the water as described with respect to Figs. 1 to 3. 100

In both the types of dynamometer described above, the load exerted by the dynamometer at any given speed is dependent upon the pressure of water which is maintained inside the power-absorbing compartment of the casing. If the resistance to the flow of water from the casing is high, it follows that the pressure of water and therefore the power consumed will be high. If the resistance to flow be diminished the power consumed will likewise diminish. In practice the adjustment of resistance is easily effected by regulating the outlet valve only, but a further means of regulation is offered in the case of the second form of the invention by manipulation of the valve K fixed between the pump discharge and the entry to casing. 110

115 What I claim as my invention and desire to protect by Letters Patent is:— 120

1. An hydraulic brake for dynamometers for measuring the power developed by rotating shafts comprising a casing, a rotor, a shaft within the casing on which said rotor is mounted, vanes formed on the rotor, vanes formed on the casing, and means automatically operated from the rotor shaft for supplying water to the rotor at a rate of flow which is proportional to the speed of rotation of the shaft. 125 130

2. An hydraulic brake for dynamometers for measuring the power developed by rotating shafts comprising a casing, a rotor, a shaft within the casing, on which said 5 rotor is mounted, vanes formed on the rotor, vanes formed on the casing, means for supplying water to the rotor at a rate of flow which is proportional to the speed of rotation of the shaft and means whereby the 10 water leaving the rotor is re-circulated through water passages in the vanes thereof.
3. An hydraulic brake for dynamometers for measuring the power developed by rotating shafts comprising a casing, a rotor, a 15 shaft within the casing on which said rotor is mounted, vanes formed on the rotor, vanes formed on the casing, means for supplying water to the rotor at a rate of flow which is proportional to the speed of rotation of 20 the shaft and means to promote a flow of water through holes formed in the rotor, the water being re-circulated from a part of the casing where the pressure is high to a part where the pressure is low from which 25 point the rotor draws its supply.
4. An hydraulic brake for dynamometers

for measuring the power developed by rotating shafts comprising a casing, a rotor, a shaft within the casing on which said rotor is mounted, vanes formed on the rotor, vanes 30 formed on the casing, means for supplying water to the rotor at a rate of flow which is proportional to the speed of rotation of the shaft, means to promote a flow of water through holes formed in the rotor, the 35 water being re-circulated from a part of the casing where the pressure is high to a part where the pressure is low from which point the rotor draws its supply and a valve to admit fresh water to the point of low 40 pressure.

5. An hydraulic brake for dynamometers for measuring the power developed by rotating shafts comprising a casing, a rotor, a shaft within the casing on which said rotor 45 is mounted, vanes formed on the rotor, vanes formed on the casing and a pump driven by the rotor shaft for supplying the water to the rotor.

In testimony whereof I have hereunto set 50 my hand.

GEORGE H. WALKER.
